UNITED STATES PATENT OFFICE

RICHARD A. BOND, OF CHAGRIN FALLS, OHIO, ASSIGNOR, BY MESNE ASSIGNMENTS, TO MULTIGRAPH COMPANY, OF WILMINGTON, DELAWARE, A CORPORATION OF DELAWARE

APPARATUS FOR MAKING HOLDING DEVICES FOR PRINTING MEMBERS

Application filed May 13, 1930. Serial No. 452,092.

This invention relates to an apparatus for forming address plates and is especially adapted to form address plates which will be suitable for ready mounting in a printing machine and adapted to print addresses either alone, as in addressing envelopes, or in conjunction with other matter, as in producing circulars. The embodiment illustrated is especially adapted for form address plates which may be readily used in rotary printing machines, such as the Multigraph. The address plate is of the type having a holding member of metal with upstanding outwardly extending projections on which printing strips are mounted. Such an address plate is shown, described and claimed in Patent No. 1,628,630, granted to Henry C. Osborn and assigned to my assignee.

The general object of this invention is to provide an effective apparatus for forming a holder for printing members, and more particularly a holder for printing strips. This holder with its strips may be used on either a rotary machine or an oscillating arm machine, when provided with suitably shaped platen members.

Another object is to provide an apparatus for forming a holding member of sheet metal, having upstanding outwardly extending projections on which suitable printing strips may be mounted, and wherein all burrs are removed from the body of the holder, and the projections made uniform and so shaped as to readily receive and retain the printing strips.

A further object is the provision of an apparatus for forming a holding member of sheet metal, wherein the body of the member is arcuate and has upstanding laterally extending projections of a uniform height and alignment to facilitate the mounting of embossed printing strips thereon.

Another object is the provision of an apparatus which will form individual holding members from a continuous roll or strip of material, and which will make upstanding projections on the members and provide each member with a bead or strengthening portion.

Another object is to provide an apparatus

for forming holding members having upstanding outwardly extending projections and shaping the edges of the projections so that embossed printing strips may be readily retained thereon.

Other objects of the invention, and features which contribute to the efficiency of operation and facilitate quantity production and economy in manufacture, will become more apparent from the following description, referring to the accompanying drawings, and the essential and novel features will be set forth in the claims.

In the drawings, Fig. 1 is a vertical longitudinal centrally located section through the portion of the apparatus which forms the projections on the holding members and sever them into individual units from a continuous strip or roll of material; Fig. 2 is a horizontal section and is indicated by the line 2—2 on Fig. 1; Fig. 3 is a front elevation of the apparatus which shapes and trims the holding members, portions of the apparatus being broken away; Fig. 4 is a horizontal section, taken through the shaping and trimming mechanism, and is indicated by the line 4—4 on Fig. 3; Fig. 5 is a vertical section and is indicated by the line 5—5 on Fig. 4; Fig. 6 is a plan, on an enlarged scale, of a portion of the feeding mechanism shown in Fig. 4; Fig. 7 is a longitudinal vertical section as indicated by the line 7—7 on Fig. 6; Fig. 8 is a transverse section as indicated by the line 8—8 on Fig. 6; Fig. 9 is a section similar to Fig. 8, but illustrating some of the parts in a different position; Fig. 10 is a transverse section as indicated by the line 10—10 on Fig. 6; Fig. 11 is a plan on an enlarged scale of a portion of the die mechanism illustrated in Fig. 4; Fig. 12 is a vertical transverse section through one pair of dies and is indicated by the line 12—12 on Fig. 11; Fig. 13 is a transverse section through another pair of die members and is indicated by the line 13—13 on Fig. 11; Fig. 14 is a section similar to Fig. 13, but showing the die members in a closed position; Fig. 15 is a horizontal section illustrating the forming rolls and is indicated by the line 15—15 on Fig. 16; Fig. 16 is a vertical transverse section illustrating one pair of

forming rolls; Fig. 17 is a vertical transverse section taken through the trimming unit and is indicated by the line 17—17 on Fig. 15; Fig. 18 is a horizontal section illustrating the trimming unit in plan and is indicated by the line 18—18 on Fig. 17; Fig. 19 is a transverse vertical section taken through the trimming unit and is indicated by the line 19—19 on Fig. 18; Fig. 20 is a vertical longitudinal section through the trimming unit and is indicated by the line 20—20 on Fig. 18; Fig. 21 is a perspective of one of the cutters, which trims the burrs from the projections and from the plate; Fig. 22 is a perspective view, illustrating the holding members, after the projections have been formed and the member sheared from the supply of material; Fig. 23 is a transverse vertical section through a holding member, and some of the projections thereof as shown in Fig. 22, and is indicated by the line 23—23 on Fig. 22; Fig. 24 is a transverse section through a holding member after it has been formed by the first pair of forming dies; Fig. 25 is a transverse section illustrating the member after it has been formed by the second pair of forming dies; Fig. 26 is an enlarged fragmentary section of a portion of Fig. 25, and illustrates the burrs which result from the punching operation; Fig. 27 is an enlarged fragmentary section through a holding member and illustrates the method of removing the burrs therefrom, and the manner of trimming the edges of the projections; Fig. 28 is a fragmentary transverse section through a portion of the holding members and is similar to Fig. 26, but illustrates the completed unit; Fig. 29 is a perspective view of a holding member in its completed form; Fig. 30 is a fragmentary transverse section through a portion of a holding member and illustrates a printing strip mounted thereon; Fig. 31 is a perspective view of a printing strip with which the holder illustrated is adapted for use; Fig. 32 is an electrical diagram and illustrates the manner in which the mechanism is controlled.

This invention contemplates the forming of a holder for printing members from a continuous strip or roll of material. A portion 50 of the strip is first corrugated, the corrugations extending transversely of the strips and suitable outwardly extending projections are upstruck from the sides of the corrugations, the rows of projections being parallel with 55 each other, and the upper surfaces thereof lying in the same plane, which is the plane of the top of the corrugations. This may be accomplished by any suitable means, such as shown in the drawings, by a forming press 10. The corrugated portion of the strip is then 60 sheared into individual units, one of which is illustrated at "W 1" in Fig. 22. As shown in the drawings, this is also accomplished by a reciprocating shear, which is associated 65 with the press 10. However any other means

such as a suitable rotary shear may be employed.

The sides of the plate, adjacent the corrugations, are now bent downwardly, forming U-shaped channels, and the body of the plate is given an arcuate form as shown in Fig. 23. A preferred means of accomplishing this is illustrated in the drawings and includes a pair of forming dies, which are associated with a suitable forming press 12. This operation likewise might be performed by suitable rolls. The outer portions of the U-shaped sides is then bent inwardly substantially normal to the inner side of the U forming a bead thereon. This may be accomplished by suitable rolls, or, as shown in the drawings, by suitable dies in the forming press, 12. The edge of the unit, which was previously turned inwardly to form the bead, is then rounded, thereby forcing the rough edge of the bead downward towards the inner surface thereof, and at the same time the downwardly extending side is bent outwardly a slight amount to prevent future distortion of the unit. As shown in the drawings, this is accomplished by a pair of forming rolls. However, it may readily be accomplished by suitable dies, operating similarly to those shown in the forming press, 12.

The burrs on the unit, which result from the punching operation are now removed. This may be accomplished by any suitable means such as shown in the drawings by a cutting unit, 15, which cuts the burrs from the edges of the projections and gives them a slight bevel or it may be accomplished by a suitable grinding operation. The unit then is given its final shape. In the drawings this is accomplished by a pair of rolls. However, it may readily be accomplished by suitable finishing dies. The units are then stacked as finished products for storing or packing.

I have explained in the three preceding paragraphs how the process in general may be carried out employing the apparatus herein shown or other apparatus as desired. It should be noted however, that the particular apparatus shown is a preferred mechanism and is comprehended within my invention herein claimed.

In the drawings, the press 10 which forms the projections on the metal strip and shears the plate from a continuous strip or roll is shown as an individual press, but it is contemplated that it may be a part of the press which forms the sides and body portions of the plate. This may readily be accomplished without materially altering either structure.

The press 10 which forms the corrugations "a" and the outwardly extending projections "b" and "c" is best illustrated in Figures 1 and 2, and comprises a frame or base 20, having upright guides or ways 21 in which a head 22 is reciprocated in any well known manner, such as by a crank shaft 23

130

which is driven from a suitable source of power such as a motor 24. Mounted on the base 20 is a male die member 35, which has upstanding ribs 36 having pins 37 associated therewith. A female die 38 is carried by the reciprocating head 22 and has channels 39 having openings 40, associated therewith, which coact with the ribs 36 and pins 37 of the lower die member 35 thereby forming the 10 corrugations "a" and the laterally extending projections "b" and "c" illustrated in Fig. 22.

The material W may comprise a comparatively thin, and substantially continuous strip 15 of rolled alloy steel, as such material provides a holder which is unusually strong and at the same time is light, compact and readily adapted for quantity production. However, any comparatively thin metal, such as zinc, 20 tin or brass, may be used as desired.

The material W is preferably supplied to the press from a continuous roll 41, carried by a suitable reel 42, mounted in brackets 43, which extend forwardly from the press (to 25 the left in Figures 1 and 2). The material passes from the roll 41 to suitable feed rolls 45, journaled in boxes 46 which are carried by standards 47 secured to the forward end of the bed 20. Suitable compression springs 30 48, retained in the standards 47, act on the upper journal boxes 46 to urge the rolls against each other, thereby gripping the material between the rolls and feeding it to the dies. Suitable driving means are provided 35 to drive the rolls continuously.

To prevent the material from warping, when the strip W is gripped by the dies, the pressure on the upper feed roll is released. To this end, the upper journal boxes 46 are 40 yoked about their respective shafts 50, which are journaled in the standards 47 and the upper faces of which are flattened, as at 51. Normally, the shafts are out of contact with the journal; however, just before the dies 45 coact, the shafts are rotated through a portion of a revolution, camming the journals upwardly against the springs 48, thereby relieving the pressure on the rolls 45. Immediately after the dies are separated, the shafts 50 are returned to their normal position by 50 suitable springs, and the rolls again act to feed the material to the dies.

The shafts 50 are actuated by the reciprocating head 22. Adjustably mounted in an 55 ear 52, of the head is a set screw or pin 53, which coacts with one arm 54 of a bell crank, rigidly secured to one of the shafts 50. The other arm 55 of the bell crank is shown as connected by a bar 56 to a suitable lever 57 60 which is rigidly secured to the other shaft 50, thereby moving both shafts in unison, and relieving the pressure on the rolls 45.

Suitable means are provided to oil the material W, thereby facilitating the stamping 65 operation, and preventing undue adherence

of the material to the dies. Immediately to the rear of the feed rolls 45 (to the right in Figures 1 and 2) are a pair of oiling rolls 58, between which the material is fed. The rolls 58 are loosely journaled in the standards 47, and the lower roll 58 rotates in a pan 59, containing suitable oil.

A stop or brake is provided to prevent movement of the material W while the dies are acting on it. A plunger 61, mounted in the ear 52 of the reciprocating head 22, is urged downwardly by a compression spring 62. The plunger 61 is adjusted, to coact with the material W slightly before the die members come together, and grip the material between the lower surface of the plunger and a suitable block 63, mounted on the base 20 of the press, thereby preventing any movement of the material. The plunger remains in contact with the material for a brief interval after the die members separate and is then carried away by the upward movement of the head. This causes the material to be stripped from the upper die 38. While the dies separate suitable pins 64, slidably mounted in the lower die 35, are urged upward by springs 65 and act to strip the material from the lower die.

The dies 35 and 38 also serve to shear the strip of material into individual units, one of which is illustrated in Fig. 22. After the first unit has been corrugated and the projections have been formed thereon, the feed roll 45 functions to advance the strip to a positive stop or block 67, thereby placing the previously formed material beyond the bite of the dies and presenting a subsequent portion of the strip thereto. As the reciprocating head 22 descends to form the next set of corrugations on the strip, a knife edge 68, rigidly secured to the die 38, coacts with a cutting edge 69, of the lower die 35 and shears the unit W1 from the strip. The sheared edge of the strip W1 then falls to a shelf or ledge 70, on the die member 35, thereby placing the unit W1 in a position to be ejected from the press by a suitable ejection bar 72.

The ejection bar 72 is slidably mounted in suitable bearings 73 which are secured to the base 20 of the press. When the head 22 reciprocates, a roller 74 mounted on the head coacts with a slot 75 in one arm of a bell crank 76, pivotally secured to an upwardly extending bracket 77 of the base, thereby rocking the bell crank about its pivot. As the head 22 descends, an arm 78 of the bell crank coacts with a slot 79 in the bar 72 and causes the end of the bar to shove the unit W1 laterally, onto a sloping bottom 80 of a magazine 81. As the head recedes, the bar is withdrawn, to a position to eject the next succeeding unit. As the next unit is ejected, it is pushed by the bar 72 against the preceding unit, and forces the latter into a vertical position in the magazine.

Suitable spring pressed ears, having beveled noses 83 enter the magazine 81, serve to maintain the plates on end, while a spring-pressed pawl 84 mounted in the runway prevents the plate from rebounding into the press.

One of the units W1 thus formed, is illustrated in Fig. 22. As shown, it has been provided with upstanding corrugations *a*, extending lengthwise of the plates, and parallel with each other. Each corrugation has been provided with a row of lips *b*, extending in one direction, and a row of lips *c*, extending in the opposite direction. These lips have been cut out of the sides *d* of the corrugations and turned upwardly. The lips *b* are staggered with reference to the lips *c*, that is to say, there is a lip *b* on one side, and immediately beyond it a lip *c* on the other side, and then a lip *b* on the first side and a lip *c* on the second side, and so on. The lips *b* and *c* lie substantially in the same plane, which is coincident with the plane of the tops of the corrugations.

The units W1 are next manually removed from the magazine 81 of the press 10 and placed in a suitable vertical magazine on the forming press 12 where the body portion of the unit is given an arcuate shape and the longitudinal edges thereof are formed into downwardly extending beaded sides.

The frame of the forming press 12 comprises primarily, a bed 100 supported by suitable standards 101, and having a longitudinally extending runway 102 for the units. Secured to this frame is an upwardly extending standard 103, which supports suitable ways, or guides 104, in which a crosshead 105 is reciprocated by a suitable crank shaft 106, which is mounted in the upper portion of the standards and is driven by a suitable motor. The head 105 carries die members 108 and 109, which are adapted to coact with corresponding die members 110 and 111 mounted in the runway 102 of the base and which dies will be hereinafter described in detail.

The units W1 are placed in a stack, one above the other, in a vertical magazine comprising upright plates 112, which have outwardly extending flanges 113 at the base thereof, by which they are secured in place on the bed 100, and the inwardly extending edge flanges 114 adapted to overhang the ends of the units. The units in this magazine rest one on top of the other, in an inverted position, the projections of each plate resting on the plate below as shown in Figs. 8 and 9.

The bottommost unit W1 in the magazine, is pushed from beneath the stack onto the die member 110, between the guides 107, by a plunger or bar 115 which is manually reciprocated between suitable guides 116 rigidly secured to a portion 100a of the base of the press, as shown in Figs. 3 to 7. A lever 117

pivoted to the base at 118 is connected by a link 119, to the bar 115. The lever 117 has a suitable handle 120, by means of which it is manually reciprocated by the operator. The foremost corners of the plunger 115 are beveled as at 121, and coact with levers 122 which are pivoted at 124 to the bed 100. The levers 122 have wedge-shaped arms 125, which are adapted to raise all but the bottom-most unit in the stack as illustrated in Figs. 8 and 9, but which are normally held out of contact with the units by springs 127. The construction is such that as the bar 115 is brought forward by the operator, the beveled nose of the bar will cam the arms 123 of the lever outwardly, causing the arms 125 to enter apertures 126 in the sides of the magazine and lift the stack of units therein a short distance, as illustrated in Fig. 9, leaving the bottommost unit W1 resting on the base 100 free from the stack and in position to be urged forward onto the die member 110 by the continued movement of the bar 115.

The die members 108 and 110 have arcuate faces which shape the body of the plate and are also adapted to form the downwardly extending sides thereof. It will be noted, as shown in Figs. 11, 13 and 14, that the lower die member 110 is slidably mounted in the recess 129 in the base 100 and is urged upwardly by springs 131, against suitable stops 132. As shown, the upper surface of the die member 110 is generally arcuate in cross section and is provided with a series of longitudinally extending parallel grooves 133, which align with and are the same depth as the corrugations *a* of the units W1, and in which the corrugations with their associated projections slide across the die. The stops 132 are rigidly secured to the bed 100 by suitable bolts 134, and have upwardly extending ribs 136, which lie adjacent the die 110. The upper die 108 is arcuate in cross section and has a plurality of downwardly extending parallel ribs 135 which are adapted to co-operate with the corrugations in the plate, the construction being such as to cause substantially the corrugated portion of the unit to be gripped between the die members. Rigidly secured to the head 105, adjacent the sides of the die 108, are blocks 137 which co-operate with the ribs 136 of the stop members 132. It will be noted that the units W1 are fed to the dies in an inverted position, as illustrated in Figures 13 and 14, and as the die members 112 and 110 are brought together, the body of the unit is arcuately shaped.

As the head 105 continues in its downward movement, it carries the lower die 110 with it, causing the edges of the unit, which have been gripped between the rib 136 of the stop 132 and the block 137, to be drawn around the rib, thereby forming the sides into upwardly extending U-shaped channels (the unit being 130

in an inverted position) as illustrated in Fig. 14.

As the upper die rises, suitable ejector pins 140 slidably mounted in the blocks 139, are urged downwardly by compression springs 141, thereby ejecting the units from the upper die member, while the compression springs 131, hereofore described, urge the die 110 upwardly, stripping the plate from the ribs 136 of the blocks 135, thereby completely freeing the plate from both die members.

The unit W2 thus formed by the dies 108 and 110 is best shown in section in Fig. 24. The body portion of the unit which carries the corrugations *a* and the projections *b* and *c*, has been given an arcuate shape or curvature in a direction transverse to the corrugations. The sides of the unit have been bent first downwardly, then outwardly and upwardly, thereby forming downwardly extending U-shaped channels *f* which are parallel with the corrugations.

After the unit has been formed, the operator again swings the lever 117, thereby carrying the bar 115 to the left (Figs. 4, 5 and 6), feeding another unit W1 from the magazine to the bite of the dies 108 and 110. As the unit is fed, the foremost edge thereof strikes the unit W2, which has just been formed, and shoves the latter onto the die member 111. The upper portion of the channels *f* slide beneath guides 145 and the corrugations *a* slide in channels 146 in the die member 111 as shown in Figs. 11 and 12.

The faces of the dies 109 and 111 are arcuately formed to conform with the shape of the unit W2. The upper die 109 has downwardly projecting ribs 147 which align with, and are the same depth as, the corrugations *a*. The die members 109 and 111 are similar in all respects to the die members 108 and 110 heretofore described.

The lower die member 111 is slidably mounted in the base 100 of the press and is normally urged upward by compression springs 148. Suitable blocks or stops 149, rigidly secured to the base 100 by bolts 150, coact with shoulders 151 on the die member and restrict its upward movement.

The guides 145 which guide the unit onto the die 111 are withdrawn as the upper die 109 descends, permitting die blocks 156 rigidly secured to the die member 109 to contact with the upper edges of the channels *f* of the unit. To this end the guides 145 are slidably mounted in recesses 157 of blocks 158 which are rigidly secured to the frame 100. The guides are held in alignment by pins 159, rigidly secured thereto, and which slide in openings 160 in the blocks 158. Suitable compression springs 161, coiled about the pins, normally urge the guides 145 against an abutment 162 on the blocks 149, thereby limiting the movement of the guides. As the upper die 109 descends, cams 164 rigidly secured

to the die member, contact with ears 165 carried by the guides, and cam the latter outward, causing them to be forced clear of the descending die and its associated parts. As the die rises, the springs 161 force the guides to their normal positions. To facilitate the entrance of the units beneath the guides, the foremost under surfaces thereof may be tapered.

The dies 109 and 111 act to bead the outer leg *g* of the channel *f*. To this end, the blocks 149 have recesses 152 into which the channels *f* are forced as the upper die descends.

The recesses 152 have downwardly extending walls 153 and 154. The walls 154 extend downwardly a short distance and are then sloped inwardly towards the die and the walls 153, as shown at 155, and then downward as at 154*a* and then inward, joining the walls 153 as shown at 153*a*. As the unit is forced downward by the descent of the upper die member, the edges *g* of the channel portions of the unit enter the recesses 152 and strike the sloping portion 155 of the walls which turns them inwardly, thereby forming a bead as shown at *h* in Fig. 25.

When the head 105 rises, the upper die is carried away from the lower die 111 and the compression spring 148 returns the latter to its normal position, thereby stripping the beaded portions of the unit W3 from the walls of the recesses 153 and freeing the unit from the dies.

As the next unit W1 is fed from the magazine by the operator, the units W2 and W3 are advanced the length of one unit. The unit W2 advances from the dies 108 and 110 to the dies 109 and 111, while the unit W3 is advanced or is shoved by the unit W2 into the bite of the forming roll unit 14.

The forming roll unit 14, as illustrated in Figs. 3, 4, 5, 15 and 16, comprises two pairs of rolls 170. Each roll is mounted on a shaft 171, journalled in bearings 172 located in standards 173 which are rigidly secured to a portion 100*b* of the base of the press. The rolls are driven by a motor 174 (Figs. 3 and 31) which is connected by a belt 175 to a pulley 176, rigidly mounted on a shaft 177 journalled in bearings 178 in a bracket 179 and one of the standards 173. Keyed to the shaft 177 is a spur gear 180, which lies between two pinions 181, one of which is secured to each upper feed roll shaft 171. Suitable pinions 182 are rigidly secured to the lower feed roll shafts 171, thereby driving the latter. The speed of this drive is such, that the rolls advance the units slightly faster than the operation of the dies, thereby preventing any jamming of the units in the runway.

The forming rolls of each pair are normally spaced apart a distance which is equivalent to the thickness of the material used for the manufacture of the units. To provide for variations in this thickness, as well as to

adapt the mechanism for different materials, an adjustment is provided by means of which the rolls may be separated or brought closer together as desired. To this end, the bearings 5 for the upper rolls are slidably mounted in ways 183 in the standards 173. Suitable compression springs 184 retained in recesses 185 in the standards act on the bearings to force the latter against transverse bars 186, 10 carried in the ways 183 of the standard, there being one such bar for each pair of rolls. The bars 186 are restrained in their upward movement by suitable set screws 188, carried by transverse members 189, rigidly secured 15 to the standards by bolts 190. To permit accurate adjustment of the rolls, each set screw 188 is provided with a suitable knob or wheel 191, and a lock nut 192 which retains the rolls in an adjusted position.

20 The forming rolls, which accurately form the arcuate face of the units, also act on the downwardly extending sides to bend them outward a slight amount, thereby reducing the springiness and the tendency of the unit 25 to distort. The forming rolls also turn the innermost edge of the bead downwardly a small amount, rounding the exposed surface thereof, so that no rough edges exist on the outer surfaces on the unit. Each upper roll 30 comprises a central or body portion 195, the surface of which is arcuate in cross section, as illustrated in Fig. 15, and which conforms to the curvature of the finished plate. Immediately adjacent the body portions 195, 35 are flanges 196, which have grooves 197, on their outer peripheries, adapted to coact with the beaded portions of the units. The edges of the body portion are tapered as at 194, the angle of the taper being slightly greater than 40 that imparted to the units by the dies.

The lower forming roll comprises a series 45 of discs 198 and 199. The discs 199 are slightly greater in diameter than the discs 198 and are adapted to fit between the rows of projections on the unit. The discs 198 coact with the upper surface of the corrugations and the projections thereof. To either 50 side of the discs 198 and 199 are flanges 200, which are so shaped as to finish the outer surfaces of the downwardly extending sides of 55 the units. The various portions of the rolls are rigidly secured to their respective shafts by suitable jamb nuts 206, which force the portions against each other and against shoulders 205 of the shafts. The angle formed by 60 the flanges 200 is somewhat greater than the angle which has been imparted to the units by the dies 109 and 111, thereby forcing the downwardly extending sides outwardly a slight amount from the position shown in dotted lines in Fig. 26, to the position shown in full lines.

It will be noted that the dies 108, 110, 109 and 111 bend the sides of the plate through 65 a greater angle than is desired for the finished

product. Thereafter the finishing or forming rolls 170 lessen this angle, or, in other words, bend the sides back a slight amount. The dies also curve the body portion of the plate a greater amount than is desired in the 70 finished product and thereafter the forming rolls lessen the curvature. This, it has been found, substantially eliminates the ordinary tendency of the finished units to spring or distort when piled one on another, the bead of one unit supporting the bead of the next 75 succeeding unit, and the body portions resting clear of each other to prevent damage to the printing strips.

The printing strip which carries the characters, by means of which the printing is accomplished, is best illustrated in Fig. 31, and comprises a sheet metal member 250, bearing upwardly embossed printing characters 251, and having inwardly curled edge flanges 252. 80 Such strips are held in place on the holder by the projections *b* and *c* of the holder, which support the strips and beneath which the flanges 252 extend. As illustrated in Fig. 30, 85 it will be noted that the edges of the projection have been tapered slightly, to conform with the inwardly turned edges of the printing strip, thereby securing the printing strips in place on the holder. The downwardly extending edges of the printing strip extend substantially to the body portion of the plate. Hence, it will be seen that any burrs, 90 remaining on the unit as a result of the stamping operations, must be removed, and the edges of the projection must be tapered.

Immediately after the unit is discharged from the first pair of rolls 170, it is forced through the trimming or cutting unit 15, which trims the burrs from the body portion of the unit, and bevels the edges of the projections so that they may readily receive and 95 retain suitable printing strips. As illustrated in Fig. 26, it will be noted that the edges of the projections have slight butts thereon, and that the edges of the openings from which the projections have been stamped also have 100 upwardly extending burrs, these burrs being the result of the stamping operation.

The cutting or burring unit 15, used to trim the burrs *B* from the units and bevel the edges of the projections as shown at *C*, is best illustrated in Figs. 3, 5, 15, 17, 18, 19 and 20. The cutting tool itself, is best shown in Figs. 21 and 27, and preferably comprises a block 220, having upwardly extending ribs 221, 110 which form a channel 222, the depth of which is equivalent to the distance from the top of the plate to the top of the projections, and which is so shaped as to permit the projections to slide along the bottom face 223 of the channel. The upper surfaces 224 of the ribs contact with the body portion of the plate at 115 225, as illustrated in Fig. 27, and the sides of the ribs contact with the sides of the projections, as illustrated at 226 in Fig. 27. The 120 125 130

forwardmost portions of the ribs are tapered as at 228, in Figs. 20 and 21, thereby forming a cutting edge along the sides and top ribs. The inner surfaces of the ribs are bevelled as 5 at 229, thereby imparting a taper to the edges of the projections, forming them so that the printing strips 250 will readily fit in place thereon. As shown in Fig. 21, I prefer to make the block 220 of two pieces of metal 10 220a and 220b, which are secured together by suitable pins 230 and a bolt 231.

As illustrated in Figs. 17 to 20 inclusive, there is one cutting tool or block 220 for each row of corrugations, the tools being held in 15 a suitable carriage 240 by means of clamping plates 241, which are bolted together by suitable bolts 242. As illustrated in Figs. 20 and 21, each of the cutting tools 220 has outwardly extending ears 243 at their bases, 20 which underlie the carriage 240, and are retained in contact therewith by the lower clamping plate 241. The upper clamping plate 241 is cut away as at 246 to receive the unit. As the cutting units 220 are substantially 25 greater in width than the center to center distance of the corrugations, it is necessary that they be staggered as shown in Fig. 18, the cutter 220, for one corrugation, lying in the foremost portion of the carriage 240 and the cutter 220 for the next corrugation lying immediately to the rear and one side thereof, and the cutter for the next corrugation lying in the forward portion of the block, and so on.

35 The cutting and trimming unit 15 is so mounted between the two pairs of rolls that it may be readily and quickly replaced. To this end, a pin 260 is rigidly secured to one of the standards 273, and projects inward therefrom. The carriage 240 is provided, at one end, with an opening 261 adapted to receive the pin 260. The other end of the carriage has a transverse opening 262 adapted to receive a pin 263, having a knurled head 264 and carried by blocks 265 which is rigidly secured to the other standard 173 by suitable bolts 275. As described, it will be seen that when the pin 263 is removed, and a new trimming unit substituted therefor, the cutting unit just removed may then be taken apart and the cutters sharpened.

As heretofore described, the plates or units W4 are forced through the cutting unit by means of the first pair of rolls, and before 55 the first pair of rolls have completely released the unit, it is gripped by the second pair of rolls, which are similar in all respects to the first pair heretofore described. The last acting pair of rolls serves to true the 60 plates and correct any discrepancies or variations which may have been imparted thereto by reason of the cutting or trimming operation.

The last acting pair of rolls 170 ejects the 65 finished units into a suitable magazine, where

they are stacked by a stacker 270. As the plates are ejected, by the last pair of rolls, the forwardmost end falls against a spring pressed pin or plunger 271, having a bevelled nose, and which enters suitable apertures in the side walls of the magazine 272. As the completed unit W5 is further ejected, the rear-most portion, as it leaves the rolls, falls to the bottom of the magazine, as illustrated at 70 273 in Fig. 5. Shortly thereafter, a suitable arm 276, pivoted to a rock shaft 277 mounted in brackets 278, is urged against the unit W5, forcing it into an upright or endwise position in the magazine, and carrying it beyond the tapered nose of a spring-pressed latch 280 which enters suitable apertures in the side walls of the magazine. A block 281 which frictionally engages the sides of the magazine, due to suitable compression springs 282, 75 serves to retain the units in an upright position, the compression strength of the spring being sufficient to retain the units in an upright position, but permitting the arm 276 to pack the units together and shove the block 281 and units rearwardly as each succeeding unit is discharged from the mechanism.

I prefer to operate the stacking arm 276 from the reciprocating head 105 of the press. To this end a roller 290 is mounted on the reciprocating head, and coacts with a notch 292 in a cam plate 291. As the head descends, the roller 290 enters the notch 292 and forces the plate rearwardly carrying with it a bar 293.

The bar 293 carries a roller 294 which coacts with a slot 295 in a rock arm 296 rigidly secured to the shaft 277, hence the downward movement of the head 105 causes the stacking arm 276 to swing downwardly to stack the units. As the head rises, the roller 290 coacts with the upper surface of the cam slot 292, and withdraws the cam plate 291 and its associated mechanism, thereby causing the stacker arm 276 to return to its normal position.

The reciprocating head is preferably set in motion by the operation of the arm 117. To this end, a switch 300 is operated by a link 301 pivotally secured to the operating arm 117 at 302, as illustrated in Figs. 4 and 6. As the operating arm 117 is swung to the left (Figs. 4 and 6) to advance the units, the link 301 which is pivotally connected to a slide bar 303 of the switch forces the latter inward, thereby camming a pawl 304 upward, and permitting it to fall into a notch 305 in the bar 303. However, as the operating arm 117 is withdrawn, the pawl 304 again contacts with the lug 306 on the bar, but this time the tendency is to swing the pawl in a counter-clockwise direction, and one ear 307 of the pawl coacts with a pin 308 rigidly secured to a vertically sliding bar 309 and cams the bar 309 upward, thereby closing the switch contacts 310 and 311 thereby completing a circuit 100 105 110 115 120 125 130

from a battery or other source of power 320, to a solenoid 314, the core of which is secured to one end of a rock arm 315, pivoted intermediate its ends to the base of the press. The 5 other end of the rock arm is connected by a link 316 to a suitable latch 317, which controls a single rotation clutch 318, diagrammatically shown in Fig. 32, and which connects the pulley to the crank shaft to cause 10 the reciprocation of the head 105.

To prevent damage to the machine if the 15 plates should jam in the runway,—one plate sliding on top or beneath another, and the reciprocating head thereafter descending—a safety switch is included in the circuit 312, as indicated at 330 in Figs. 32 and 4. As shown, this switch comprises a pawl 331 normally urged into the runway by a spring 332, and which controls a switch contact 333. It 20 will be noted that when a plate is present in the runway, as illustrated in Fig. 32, the downwardly extending sides of the plate cam the pawl outwardly, closing the contact 333 and closing the circuit, thereby permitting the 25 solenoid to operate the clutch. However, in case no plate is present, the pawl 331, will be swung into the runway by the spring 332, and the contact 333 will be opened, thereby 30 opening the circuit between the switch 312 and preventing the operation of the solenoid 314, until the plates in the runway have been straightened and their relative positions corrected.

I claim:—

35 1. In a machine for forming holders for printing members, the combination with a magazine adapted to contain a pile of blanks, a pair of levers on opposite sides of the magazine pivotally mounted on stationary parts of the machine and having cam ends, and a plunger for feeding the bottommost blank, the plunger having an inclined member to engage the levers opposite the cam ends to force the engaged ends outwardly and the 40 cam ends inwardly to raise the pile of blanks above the bottom blank.

2. In a machine for making holders for printing members, the combination of a pair of coacting blocks having coacting faces, 45 means providing grooves at the opposite sides of one of the blocks, there being provision for relative movement between said means and said block, the outer wall of such groove gradually approaching the block, and abutments on the opposite sides of the other block, said abutments being adapted to engage inverted trough portions at the sides of the blank and force them into the said converging groove to curl in the edges of the 50 blank.

3. In a machine for making holders for printing members, the combination of a pair of coacting blocks having coacting faces, means providing grooves at the opposite 55 sides of one of the blocks, abutments on the

opposite sides of the other block, said abutments being adapted to engage inverted trough portions at the sides of the blank and force them into the said grooves to curl in the edges of the blank, laterally moving guards adapted to overhang the inverted troughs of the blank, and means for forcing said guards laterally as the blocks approach each other.

4. In a machine for making holders for 75 printing members, the combination with means for forming blanks with upstanding projections, of two pairs of feeding rolls and a trimming device located between them, said trimming device having edges adapted to engage and remove portions of the projections on the blank.

5. The combination with means for forming a blank with rows of upstanding projections, of a pair of coacting rolls adapted to feed such blank lengthwise of the projections, a second pair of rolls spaced in advance of the first pair, a trimming device located between the two pairs of rolls, said trimming device being adapted to form a bevel on the edges of the projections as the blank passes from the first to the second pair of rolls.

6. The combination with dies for forming a blank with rows of upstanding projections, of a pair of coacting rolls adapted to feed the blank lengthwise of the projections, means for feeding the blank successively to the dies and then to the pass of said pair of rolls, a second pair of rolls similarly formed spaced in advance of the first pair, a distance less than the length of the blank, and a trimming device located between the two pairs of rolls.

7. The combination with means for forming a blank, of a pair of coacting rolls adapted to feed the blank, means for moving the blank to the pass of said pair of rolls, a second pair of rolls spaced in advance of the first pair, a trimming device located between the two pairs of rolls, said trimming device being adapted to act as the blank passes from the first to the second pair of rolls, one roll of each pair having floating bearings, a yoke acting on said bearings, and an adjusting device engaging the yoke.

8. A machine for making holders for 115 printing members, the combination with means for forming a blank with upstanding corrugations having laterally projecting ribs at their ridges, of a pair of truing rolls through the pass of which the blank is fed, and means for adjusting one of said rolls toward and away from the other roll for different thicknesses of stock.

9. In a machine for making holders for 125 printing members, the combination with means for guiding and feeding blanks having parallel rows of upstanding projections, of a pair of rolls, a trimming device adapted to engage a blank while a portion thereof is between said rolls, a removable carriage for 130

supporting the trimming device, said carriage comprising a member carrying a number of trimming units, each unit being adapted to engage a single row of projections and means for so supporting the member that it may be removed with all of the trimming units.

10. In a machine for making holders for printing members, the combination with a magazine for blanks, a pair of coacting dies adapted to act on the blank, manual means for feeding a blank to the dies, means for automatically operating said dies, means for preventing the operation until after the blank has been properly put into position between the dies, said means being actuated by the back stroke of the feeding means.

11. In a machine for making holders for printing members, the combination with a magazine for blanks, a pair of coacting dies adapted to act on the blank, means for automatically operating said dies, means for preventing the operation until after the blank has been properly put into position between the dies, said means including a plunger adapted to move the blank into proper position, and an electric switch operated by the plunger on its return stroke.

12. In a machine for making holders for printing members, the combination of means for partially forming the blank, means for feeding the partially formed blank, a pair of forming rolls to which it is fed, a pair of dies adapted to act on the fed blank before it passes to the rolls, and a safety device including a pawl extending into the runway of the formed holder between the dies and the forming rolls for preventing a subsequent operation of the dies if the product thereof is not properly advanced.

13. In a machine for making holders for printing members, the combination of means for feeding blanks successively, two pairs of dies adapted to act successively on the fed blank, and a safety device for preventing operation of either pair of dies unless the blanks therefore are properly positioned, said device including two electric switches in series in a circuit controlling the actuator for the dies, one of these switches being closed consequent upon the advancement of a blank to the first pair of dies and the other switch being closed consequent upon the advancement of a blank from the second pair of dies.

14. In a machine of the character described, the combination of means for carrying a supply of blanks, two pairs of dies adapted to act successively on such blanks, a pair of forming rolls to which the doubly stamped blank passes, means for shoving three blanks simultaneously and in series, one from the supply to the first pair of dies, one from the first pair of dies to the second pair of dies, and one from the second pair of dies to the forming rolls, and safety

devices for preventing the starting of the operation of the dies unless two blanks are in proper position between them.

15. In a device for making holders for printing members, the combination of a pair of die blocks having complementary concave and convex coacting faces, ribs at the opposite sides of one of the blocks, coacting grooves at the opposite side of the other block, the ribs and grooves being farther apart than the coacting faces, one of said blocks and said members on opposite sides thereof being movable as a unit whereby the faces first act to curve the intermediate region of the plate before the ribs and grooves act to form trough shaped portions at the margin thereof, one of the blocks being also movable relative to the members on opposite sides thereof.

16. In a device for making holders for printing members, the combination of a pair of die blocks having coacting faces, ribs at the opposite sides of one of the blocks coacting grooves at the opposite side of the other block, the ribs and grooves being farther apart than the coacting faces, whereby the said faces may first engage the intermediate region of the plate before the ribs and grooves act to form trough shaped portions at the margin thereof, a spring adapted to support the block between the ribs and the ribs being carried by separate blocks at the sides of the spring mounted block, whereby relative movement is allowed between said blocks.

17. In a machine for making holders for printing members, the combination of a pair of die blocks having complementary convex and concave faces thus adapted to curve the intermediate region of the plate, means on opposite sides of one of the blocks having narrow grooves adjacent the sides of the block, said block being mounted for movement independent of the means for carrying the grooves, whereby the plate may be first engaged in the intermediate region, and thereafter the plate with the movable die block moved relatively to the blocks carrying the grooves to bend inwardly the trough-shaped edges of the plate.

18. In a machine for making holders for printing members, the combination of a pair of die blocks having coacting faces adapted to engage the intermediate region of the plate, means on opposite sides of one of the blocks having grooves adjacent the sides of the block, said block being mounted for movement independent of the means for carrying the grooves, whereby the plate may be first engaged in the intermediate region, and thereafter the plate with the movable die block moved relatively to the blocks carrying the grooves to bend inwardly the trough-shaped edges of the plate, a pair of guards adapted to overhang the trough-shaped edges of the plate, springs pressing said

guards toward the corresponding die block, said guards having inclined shoulders, and a pair of cams associated with the other die block and adapted to act on said shoulders as the dies are brought together to force the guards outwardly and thus free the trough-shaped edges to the action of shoulders carried on the opposite sides of the die.

19. In a machine for making holders for printing strips, the combination of means for forming a blank and for feeding it, of a pair of rolls through which it passes, a stacking device beyond the pair of rolls comprising a receptacle with a detent adapted to engage the delivered holder as it drops toward the vertical position, and a packing arm adapted to swing against the delivered plate and force it beyond the detent.

20. In a machine for making holders for printing strips, the combination of means for forming a blank and for feeding it, of a pair of truing rolls through which it passes, a stacking device beyond the pair of truing rolls comprising a receptacle for the delivered holder as it drops toward the vertical position, a rock shaft, a packing arm mounted on the rock shaft adapted to swing against the delivered plate and advance it, and mechanism for rocking the packing arm, said mechanism being actuated by the operation of a die which forms the plate.

21. In a machine of the character described, the combination of a pair of blocks having coacting faces adapted to form an intermediate region on a blank, a pair of die members on opposite sides of one of the blocks, a pair of die members on opposite sides of the other block adapted to coact with the first mentioned pair, there being provision for relative movement between one of the blocks and the members on opposite sides thereof, and means for moving one of the blocks and the members on opposite sides thereof toward the other block, and continuing such movement after the coaction of the two blocks.

22. In a machine of the character described, the combination of a pair of blocks having coacting faces adapted to form an intermediate region on a blank, a pair of ribs on opposite sides of one of the blocks, a pair of recesses on opposite sides of the other block, one of said pairs being rigid with its block and there being provision for relative movement between the other pair and its block, and means for moving one of the blocks and the members on opposite sides thereof as a unit toward the opposing block and continuing the movement after the action of the two blocks to cause coaction of the ribs and recesses.

23. In a machine for making holders for printing members, the combination of two pairs of rolls, a trimming device adapted to be mounted between said pairs and having

a number of trimming members removable as a unit without disturbing the relation between them, and means for supporting the trimming device.

In testimony whereof, I hereunto affix my signature.
